UNITED STATES PATENT OFFICE.

SOLOMON WOLERSTEIN, OF NEW YORK, N. Y.

COMBINED MATCH-SAFE AND TICKET-HOLDER.

SPECIFICATION forming part of Letters Patent No. 413,006, dated October 15, 1889.

Application filed December 4, 1888. Serial No. 292,641. (No model.)

To all whom it may concern:

Be it known that I, SOLOMON WOLERSTEIN, of New York, in the county of New York and State of New York, have invented a certain 5 new and useful Improvement in a Combined Match-Safe and Ticket-Holder, of which the following is a specification.

My improvement relates to a combined match-safe and ticket-holder, in which the 10 matches are contained within a box or receptacle and the tickets are contained within a pocket upon the exterior of the match-safe, which pocket is movable away from and toward the match-safe and exerts a yielding 15 pressure upon the tickets contained within it, so as to hold them against the side of the match-safe and prevent their accidental displacement.

I will describe in detail a match-safe and 20 ticket-holder embodying my improvement, and then point out the novel features in the claims.

In the accompanying drawings, Figure 1 is 25 a side view of a match-safe and ticket-holder embodying my improvement. Fig. 2 is a horizontal section taken on the line $x-x$, Fig. 1. Fig. 3 is an end view, the cover for the match-safe being open. Figs. 4, 5, and 6 are details of construction.

30 A designates the match-safe. It has an open end provided with a cover A', acutated by a spring a in the usual manner, and retained when closed by a spring-catch a' .

B designates the pocket for tickets. This 35 pocket is provided with side portions b and one end portion b' . When the pocket is in position upon the match-safe, the portions b b' extend through a suitably-formed slot b^2 , formed in one side of the match-safe and ad-

40 jacent to the edges and one of the ends thereof. Upon the pocket B are formed lips b^3 , which, as shown, are struck up from the metal of which the pocket is formed. These lips, when the pocket is in position on the match-safe, 45 are upon the outside of the match-safe and may be grasped to move the pocket bodily outward, in order to facilitate the insertion of the tickets within the pocket. Upon the sides of the pocket, and, as shown, secured to lips

50 b^4 , also struck up from the metal of the pocket, are springs b^5 , shown as flat and having up-

turned ends, which ends, when the pocket is in position on the match-safe, bear upon the inner-surfaces of portions b^6 of the match-safe which are between the slot b^2 and the side 55 edges of the match-safe. When the pocket B is moved outwardly by grasping the lips b^3 , it is so moved against the resistance of the springs b^5 , and when the grasp upon the lips b^3 is removed the springs operate to return 60 the pocket to its normal position, and thus operate to press the tickets firmly against the side of the match-safe and to retain them until it is desired to remove them. This latter may be done, of course, by again moving the 65 pocket B outwardly. I prefer to inclose the sides b and end b' of the pocket, together with the springs b^5 , so that the interior of the match-safe will present a substantially smooth surface, and the movement of the pocket will not 70 interfere with the matches contained in the match-safe. For this purpose I employ an inner jacket D, provided with side walls d , and, as shown, with an end wall d' as well as a bottom piece d^2 . This jacket is of such 75 width only that when inserted in the match-safe the side pieces of the pocket B and the springs b^5 will be contained between the side walls d of the jacket and the edge walls of the match-safe. Upon the side walls d of the 80 jacket are outwardly-turned lips d^3 , which lips extend to the edge walls of the match-safe when the jacket is in position, and thus wholly close the spaces between the jacket and the edge walls of the match-safe. This is shown 85 more clearly in Fig. 5. By this arrangement the interior of the match-safe is caused to present a substantially smooth surface. The jacket D may be secured within the match-safe by means of solder.

90 What I claim as my invention, and desire to secure by Letters Patent, is—

1. The combination, with a match-safe, of a pocket for tickets upon the exterior thereof made separate from the match-safe, said pocket having side portions extending into the interior of the match-safe, and springs for forcing the pocket toward the match-safe, substantially as specified.

95 2. The combination, with a match-safe, of a pocket for tickets upon the exterior thereof made separate from the match-safe and hav-

ing side portions extending into the interior of the match-safe, springs for forcing the pocket toward the match-safe, and a jacket within the match-safe, in which said springs are contained, substantially as specified.

3. The combination, with a match-safe, of the pocket B, having portions extending into

the interior of the match-safe, springs b⁵, and the jacket D, provided with lips d⁶, substantially as specified.

SOLOMON WOLERSTEIN.
